HONE

Harold L. Blood, Worcester, Mass., assignor to
 The Heald Machine Company, Worcester, Mass.,
 a corporation of Massachusetts

Application November 4, 1936, Serial No. 109,125

7 Claims. (Cl. 51—73)

The present invention relates to a hone and particularly to a hone adapted for use in the finishing of tapered or cylindrical surfaces, as for example, the raceway on the inner race of a 5 roller bearing.

In prior devices of this character, the honing member, which is preferably in the form of an abrasive stone, has been relatively small in size and is soon worn down to a point where it is no 10 longer usable and must be replaced. This is especially true where the hone is incorporated in a high speed automatic machine for rapid finishing successively of a plurality of work-pieces. It will be apparent that whenever one of the honing 15 stones becomes worn so as not to be usable, the machine must be stopped for replacement of the stone. Not only is this a waste of productive machine time, but it also makes the honing operations relatively expensive since a substantial portion 20 of each honing stone must be discarded. The principal object of the present invention is to provide an arrangement by which a relatively large stone may be used for the honing operation so that the stone will last a relatively long 25 time before replacement is required.

Furthermore, when new honing stones are substituted for worn ones, the new stones must be dressed by a suitable dressing tool to the proper shape to correspond to the taper and curvature 30 of the surface being honed. A further object of the invention is to provide an arrangement which will permit the use of a stone of substantial size which can be adjusted within the carrying members, but which will avoid the necessity for dressing operations after each adjustment.

Other and further objects and advantages of the invention will hereinafter more fully appear from the following detailed description taken in connection with the accompanying drawing, in 40 which—

Fig. 1 is a sectional view through a hone embodying the invention, the section being substantially along the broken line 1—1 of Fig. 2.

Fig. 2 is an end elevation of the hone of Fig. 1 45 with parts broken away.

Fig. 3 is a side elevation of one of the hone elements.

Fig. 4 is a side elevation of the lever which carries the honing stone.

Like reference characters refer to like parts in the different figures.

With reference first to Fig. 1, the hone embodying the invention is mounted on a spindle 1 journalled in a housing 2 and the spindle has an 50 axially slidable plunger 3 by which to procure

expansion and contraction of the hone. One form of mechanism for expanding and contracting the hone is fully described in the copending application of Blood and Schmidt, Serial No. 103,725, filed October 2, 1936. It is sufficient to 5 note for the purpose of the present application that movement of the end of the rod 3 to the right procures movement of the honing stones into operative position, and movement of the rod to the left withdraws the stones from operative position, the movements of the rod being imparted by a suitable mechanism.

The hone embodying the invention comprises an arbor 4, which, as best shown in Fig. 3, has a plurality of radial slots 5 therein. The arbor also has a cylindrical hub 6 for attachment of the hone to the end of the spindle 1. A lever 7 is positioned in each of the slots 5 and has an arcuate lug 8 at the inner end thereof for engagement in a corresponding arcuate recess 9 in the 20 end of a member 10 positioned in a central bore in the arbor 4. The arcuate lug 8 and cooperating recess 9 provide a free pivotal connection between the lever and the member 10 so that any one of the members may be readily replaced without difficulty. The member 10 is held against movement within the arbor by a pin 11 and has a plurality of radially extending spring pressed plungers 12 engaging with the corresponding levers 7 between opposite ends thereof for urging 25 said levers outwardly relative to the arbor. A sleeve 13 surrounds the arbor and has a plurality of bevelled surfaces 14, each of which is engageable with a roller 15 positioned between the corresponding bevelled surface and a notch 16 on the 30 adjacent lever 7.

A spindle 16 is axially slidable within the arbor and has secured to the end thereof a member 17, having a plurality of integral radially extending fingers. The fingers on the member 17 are positioned at the bases of the several slots 5, and the ends thereof engage with the sleeve 13 to urge the latter to the right in response to the movement of the spindle 16 to the right, the latter being shifted by the corresponding movement of 40 the actuating rod 3. It will be noted that as the sleeve 13 moves to the right, each roller 15 is carried to the right from a surface 18 of the notch 16 in the lever 7, in which the roller is positioned, to a surface 20 making a substantial angle with the longitudinal axis of the lever 7, so that the levers will be moved quickly into position. The plunger 12 holds the corresponding lever 7 against the roller 15 at all times. The notch 18 in each 45 of the levers 7 is so arranged that the roller 15 55

is held in its operative position between the lever and the cooperating bevel surface 14 at all times.

The outer end of each lever 7 has a rectangular opening 21 substantially at right angles to the longitudinal axis of the lever, and the end of the latter, beyond the opening, is also split, as at 22, to provide for clamping the lever against a honing stone 23 in the form of a bar of abrasive material, the latter corresponding in cross-section to the opening 21, and being positioned therein. A clamping screw 24 provides for locking the stone 23 in position in the lever and makes possible an adjustment of the bar in the lever after the end of the bar is worn to an appreciable amount.

The stone is originally dressed to a surface represented by the line 25, Fig. 1, which, extended, passes approximately through the center of the arcuate lug 8 about which the lever 7 oscillates. The originally dressed surface of the stone is obviously arcuate to correspond to the curvature of the workpiece to be honed, and the angle between the dressed surface of the stone and the inner face 29 of the stone is slightly more than a right angle. The stone is then used until the honing surface thereof is worn down to a surface represented by the line 26, Fig. 1, which also passes approximately through the center of the arcuate lug 8 and which makes an angle with the outer face 28 of the stone substantially equal to the angle between the inner face 29 of the stone and the line 25. The mean line of wear, represented by a line 27, Fig. 1, midway between the lines 25 and 26, is at right angles to the sides of the stone 23, and the angles between this line and the lines 25 and 26, respectively, are equal. The angle between the outside face 28 of the stone and the line 25 is thus equal to the angle between the inside face 29 and the line 26. By this arrangement, the stone when worn to the line 26 can be adjusted by turning the stone in the lever so that the inside face 29 becomes the outside face, and advancing the stone longitudinally until the end of the stone assumes a position represented by the line 25, with which the end of the stone will coincide, being at the same angle to the now outside face 29.

In the operation of the device the hone is normally expanded into inoperative position by a movement of the plunger 3 to the left, thereby allowing a corresponding movement of the sleeve 13 to the left and permitting the honing stones to move outwardly away from the workpiece. With the hone in the expanded position, a workpiece *a* is placed in the operative position shown, being supported in this position on any suitable workholder, not shown. A movement of the plunger 3 to the right will then move the honing members inwardly into engagement with the outer tapered surface of the workpiece for a honing operation thereon. The stones 23 have initially been dressed to conform to the taper and curvature of the workpiece surface, the dressed surface being represented in Fig. 1 by the line 25, which, as above stated, passes substantially through the point of oscillation of the lever 7.

The honing operations are performed in the usual manner with each successive operation terminated by any suitable mechanism, which may be, for example, the timing mechanism of the Blood and Schmidt application, Serial No. 103,725, filed October 2, 1936. After the stone is worn to a predetermined extent, as when the face of the stone reaches a position represented by the line 26, which also passes approximately through the point of oscillation of the lever 7, the

stone 23 is shifted within the lever 7 to compensate for the wear on the stone.

During the preceding honing operations, the angle of the honing surface of the stone relative to the longitudinal axis thereof has changed substantially, and if the stone is merely advanced longitudinally in the lever 7, the honing face will no longer be in the proper relation to the workpiece surface. However, the opening 21 through the lever 7 is so arranged that the longitudinal axis of the stone is at right angles to the medial line of wear, represented by the line 27, and thus when the stone 23 is not only advanced to compensate for wear thereon, but is turned so that the edge nearest to the clamping screw 24 assumes a position remote therefrom, the cutting surface of the stone will then be in the proper relation to the workpiece surface.

Although it is above stated that the stone is originally dressed to a surface represented by the line 25 which is not at right angles to the axis of the stone, it will be apparent that in certain instances the stone may be originally dressed to any surface between the lines 25 and 26 so long as the amount of wear does not extend beyond the line 26 and so long as the longitudinal adjustment of the stone, after having been worn to a point represented by the line 26, is sufficient to bring the operative surface into a position represented by the line 25.

It will be understood that the machine may be arranged to provide for automatic stopping of the machine, after a predetermined amount of wear on the stone, by incorporating in the arrangement disclosed the automatic control mechanism of the copending application of Blood and Schmidt, Serial No. 103,725, above referred to. By this arrangement the stone will not be worn beyond a position represented by the line 26 before the machine is stopped to provide for a reversal and advance of the stone within the carrying lever to compensate for wear thereon. The actual spacing of the surfaces represented by the lines 25 and 26 is much smaller than the showing on the drawing which is greatly exaggerated for clarity. It will be further apparent that the lines 25 and 26 need not pass directly through the axis of oscillation of the lever 7, but may be spaced somewhat therefrom without introducing a measurable error in the finished surface of the workpieces being honed.

From the foregoing, it will be apparent that the hone provides for the mounting of relatively large honing stones which can be used for a substantial time before replacement is necessary, these stones being arranged so that once the cutting surface has been shaped (as by dressing) to correspond to the workpiece surface, no further shaping operations will be necessary during the life of the stone. The adjustment of the stones relative to the supporting structure for compensating for wear without necessitating a further dressing operation, involves the advancing of the stone relative to the supporting structure in a direction substantially at right angles to the honing face, or to the medial line of wear. The stone is also turned relative to the supporting structure through an angle of 180° about an axis substantially at right angles to the honing face.

I claim:

1. In a hone, an arbor, a plurality of levers mounted thereon, a honing element carried by each lever, a sleeve axially slidable on the arbor, and a connection between the sleeve and each lever for simultaneous oscillation of the levers.

- in response to movement of the sleeve, said connection including a roller engageable by the sleeve and each lever, one of said elements engageable with the roller having a notch in which the roller is located. 5
2. In a hone, an arbor, a plurality of levers mounted thereon, a honing element mounted on each lever, a member axially slideable relative to said arbor, and a connection between the member and each lever for simultaneous oscillation of the levers in response to movement of the member, said connection including a roller engageable by the member and each lever one of the elements engageable with the roller having a 15 notch therein in which the roller is located.
3. In a hone, an arbor, a lever pivotally mounted for movement on said arbor, a honing member carried by the lever, a sleeve surrounding the arbor and lever and axially slideable on the arbor 20 for moving the lever into and out of operative position, and a roller positioned between and engageable by the sleeve and the lever, one of the elements engageable by the roller having a notch in which the roller is positioned.
- 25 4. In a hone, an arbor, a lever pivotally mounted on the arbor, said lever having a free pivotal connection with the arbor, a honing member carried by the lever, a sleeve surrounding the arbor and positioned outside of the lever, and a connection between the sleeve and lever for urging the latter into and out of operative position in response to axial movement of the sleeve, said sleeve by its location outside of the lever holding the lever in engagement with the arbor.
5. In a hone, an arbor, a lever pivotally mounted on the arbor, said lever having a free pivotal connection with the arbor, a honing member carried by the lever, a sleeve surrounding the arbor and positioned outside of the lever, a connection 40 between the sleeve and lever for urging the latter into operative position in response to axial movement of the sleeve, said sleeve by its location outside of the lever holding the lever in engagement with the arbor.
- into operative position in response to axial movement of the sleeve, said sleeve by its position outside of the lever holding the lever and arbor in interengagement, and means for normally urging the lever toward the sleeve and out of operative 5 position.
6. In the honing of workpieces by a honing member carried by a pivotally mounted lever, the honing member being adjustable in the lever in a direction substantially perpendicular to a plane passing through the working face of the member and the pivotal support of the lever, the step which involves adjusting the member longitudinally in the lever and simultaneously turning the member through an angle of 180° about its 10 longitudinal axis after the member is worn down so that the working face is inclined to the longitudinal axis of the member, the extent of longitudinal adjustment being substantially equal to twice the amount that the member is worn away 15 beyond the point where the face of the member is at right angles to the longitudinal axis thereof.
- 20 7. In the honing of workpieces by a honing member carried by a pivotally mounted lever, the honing member being adjustable in the lever in a direction substantially perpendicular to a plane 25 passing through the working face of the member and the pivotal support of the lever, the working face of the member being originally inclined to the longitudinal axis thereof, the step which involves adjusting the member longitudinally in the lever and simultaneously turning the member through an angle of 180° about its longitudinal axis after the member is worn down so that the 30 working face thereof is inclined to the longitudinal axis in the opposite direction to its original inclination and at substantially the same angle.
- 35
